Jos. Lipic Pen Co., St. Louis, Mo., a corpora-
tion of Missouri

Application January 30, 1942, Serial No. 105,527

Term of patent 14 years

To all whom it may concern:

Be it known that I, Joseph G. Lipic, Jr., a citizen of the United States of America, residing in the city of St. Louis, State of Missouri, have invented a new, original, and ornamental Design for a Deck Thermometer or Similar Article, of which the following is a specification, reference being had to the accompanying drawing, forming a part thereof.

Fig. 1 is a top plan view of a desk thermometer or similar article, showing my new design;

Fig. 2 is a front elevational view; and

Fig. 3 is a side elevational view thereof.

I claim:

The ornamental design for a desk thermometer or similar article, as shown.
